UNITED STATES PATENT OFFICE.

AMAZIAH GARNER, OF LYNCHBURG, OHIO.

DESIGN FOR A SPOON.

SPECIFICATION forming part of Design No. 25,168, dated February 18, 1896.

Application filed January 4, 1896. Serial No. 574,390. Term of patent 7 years.

To all whom it may concern:

Be it known that I, AMAZIAH GARNER, of Lynchburg, in the county of Highland and State of Ohio, have invented a Design for Spoons, of which the following is a specification.

My invention is a new and useful design for a spoon.

The essential feature of my design consists in a cover for the bowl of a spoon cut away at the forward end, said cut-away portion being shaped in a peculiar manner, as herein-after described.

The drawing hereto annexed fully illustrates my invention, and referring thereto A represents the handle, and B the bowl.

C represents the cover, which extends across

the top of bowl, but cut away at the forward end, as shown at D, the edges of said cut-away portion being straight, as shown at E, ²⁰ and then curved inward, as at F, then slightly outward, as at G, and then inward again, as at H, converging at a point I about the longitudinal center of the bowl.

Having thus described my invention, what I claim as new, and desire to secure by Letters Patent, is—

The design for a spoon, substantially as herein shown and described.

AMAZIAH GARNER.
